(57) **CLAIM**

The ornamental design for a tool identification attachment, as shown and described.

DESCRIPTION

FIG. 1 is a left-side elevational view of a tool identification attachment showing our new design;

FIG. 2 is a right side elevation view thereof;

FIG. 3 is a perspective view thereof;

FIG. 4 is a front elevation view thereof;

FIG. 5 is a rear elevation view thereof;

FIG. 6 is a top view thereof; and,

FIG. 7 is a bottom view thereof.

Indicia rendered in broken line and other broken lines in the drawings are for illustrative purposes only and are hereby disclaimed as forming part of the claimed invention.
